ABSTRACT: This invention relates to an ingot bundle. More particularly, the invention relates to an ingot bundle comprising a plural uneven number of layers of ingots, each layer including an even plural number of parallel juxtaposed ingots, each ingot being elongated and having a downward extending foot portion therebetween, the distance between the foot portions being such as to extend downwardly beyond the sides of the next adjacent lower layer of ingots whereby all of the layers except the top layer are held in interlocking relationship and including a wire encompassing the bundle holding all of the layers thereof together, the downward extending foot portions on the ingots making up the bottom layer providing fork lift blade receiving space.

INGOT BUNDLE

BACKGROUND AND OBJECTS OF THE INVENTION

In the manufacture of raw metal, such as aluminum, magnesium, and so forth, it is customary to form the product in ingots. For convenience of users these ingots are normally arranged to have a shape, configuration and weight so that they can be conveniently handled.

Since raw metal is usually low cost per pound product the shipping, packaging, and handling charges must be reduced as much as possible. For this reason it is not normally possible for raw metal ingots to be crated or otherwise packaged for sale, storage, distribution and shipment as is the case with most other manufactured products. It is thus desirable to provide a bundle of ingots capable of transportation, storage, shipment, and handling with a minimum of expense, but nevertheless with a maximum degree of safety and integrity of the shipping configuration, that is, such bundle design must be such that the bundle cannot be easily broken during the rough treatment normally encountered in shipping nor can the ingots become loosened from the bundle handling and transportation. As examples of the efforts of others in providing bundle designs, reference may be had to the following U.S. Pat. Nos.: 3,017,042; 2,400,197; 2,720,967; 2,720,968; 3,007,586; 3,154,391; 3,161,477; 674,093; 2,119,112; 2,420,625; and others.

All of the bundle arrangements and ingot configurations disclosed in the above-mentioned United States patents and the other known literature relating to the subject matter, have taught arrangements having various degrees of success. The principal object of this invention is to provide a bundle design which achieves a degree of economy, simplicity, and shipping integrity not revealed in the above referred to patents or the other known art relating to the subjects matter.

It is therefore an object of this invention to provide an improved bundle arrangement for ingots.

Another object of the invention is to provide an improved ingot design capable of arrangement in an improved bundle.

These general objects, as well as more specific objects of the invention, will be understood by reference to the description and claims taken in conjunction with the attached drawings.

DESCRIPTION OF THE VIEWS

FIG. 1 is an isometric view of a bundle of ingots arranged according to this invention.

FIG. 2 is a cross-sectional view taken along the line 2-2 of the bundle of FIG. 1.

DETAILED DESCRIPTION

In the drawings a bundle of ingots in an arrangement according to the invention is shown. In the illustrated embodiment of the invention there are 13 layers of ingots, designated as 8A through 8M. Each layer consists of four paralleled ingots 10. The number of paralleled ingots 10 in each layer 8 is not significant to the invention except that there preferably is an even number of ingots 10 in each layer. The number of layers is not significant to the invention except that there must be an uneven number of layers in that it is necessary that the ingots 10 in the bottom layer 8A lie in the same direction, or be parallel to, the ingots in the top layer 8M.

Each of the ingots 10 includes an elongated bar portion 14 and an integral downwardly extending foot portion 16 at each end of the bar portion. The length between the foot portions of each ingot is just slightly greater than the sum of the width of the bar portions of the ingots making up a layer. As an example, in the illustrated arrangement wherein there are four paralleled ingots in each layer, the length between foot portions 16 is just slightly greater than the sum of the widths of

four ingot. By this arrangement the downwardly extending foot portions in the stacked arrangement overlap the next lower layer of ingots so that the total stack of ingots, except for the upper layer 8M, is interlocked into position.

The alternate layers above the bottom layer, that is, layers 8B, 8D, 8F, 8H, 8J, and 8L in the illustrated embodiment, are arranged to provide a slight space 18 between the two center ingots. Received in the spaces 18 and looping about the entire bundle in a plane perpendicular to the lengths of the ingots in the bottom layer 8A and top layer 8M is a wire loop 20. In practice, the loop 20 is normally formed of a length of wire positioned about the bundle in the position shown and tied at 22. Tying the wire at 22 may be accomplished manually, or by means of strapping tools, including pneumatic strapping tools.

The configuration of the ingot 10 is such that when the bundle as shown in the drawings is setting on a flat surface space between the foot portions 16 of the ingots making up the bottom layer 8A a space is provided for receiving a forklift blade so that the bundle may be easily moved around for transportation and storage by means of a forklift truck.

While the size and configuration of the ingot design may vary considerably, in one embodiment which has been tested, each ingot was approximately 2 feet long. The bar portion 14 had a cross section in which the height was 2½ inches and the width approximately 6 inches. The foot portions 16 extends to a length of approximately 2½ inches below the lower surface of the bar portion 14. A raw magnesium ingot having this configuration and these dimensions has weight of approximately 40 to 42 pounds. In the arrangement illustrated wherein the bundle included 13 rows of four ingots each, totaling 52 ingots, the total weight was approximately 2,080 pound, or approximately 1 ton. A number 10 gauge high strength steel wire 20 was used. A bundle of ingots of the above described size, utilizing 10 gauge wire, withstood severe tests, including tipping the bundle completely over without the integrity of the bundle being destroyed.

While the invention has been described with a certain degree of particularity it is manifest that many changes may be made in the details of construction and the arrangement of components without departing from the spirit and scope of this disclosure.

I claim:

1. A bundle of ingots comprising:
a plural uneven number of layers of ingots stacked one layer on the other, each layer of ingots comprising an even plural number of paralleled juxtaposed ingots, each ingot comprising an elongated bar portion of flat, substantially rectangular cross section perpendicular the length thereof and an integral downwardly extending foot portion at each end, the length between said foot portions being slightly greater than the sum of the widths of bar portions of the ingots making up a layer, each layer above the bottom layer being arranged perpendicular the adjacent lower layer whereby the foot portions of the ingots in each layer except the bottom layer extend downwardly below the upper surface of the layer immediately therebelow whereby each layer except the top layer is thereby held in paralleled juxtaposed position, the alternate layers beginning with the layer immediately above the bottom layer being arranged to provide a space between the two center ingots; and
a closed loop wire encompassing the stacked layers of ingots in a plane perpendicular the length of the ingots in the bottom and top layer, said wire being received in said space between the center ingots of the said alternate layers of ingots, the foot portions of the ingots in the bottom layer providing a forklift blade receiving space therebetween.
